PULVERIZER

Norwood H. Andrews, Moorestown, N. J., assignor
to International Pulverizing Corporation,
Moorestown, N. J., a corporation of New Jersey

Application September 7, 1942, Serial No. 457,536

2 Claims. (Cl. 241—39)

This invention relates to apparatus for the particle size reduction of pulverulent substances. It is more particularly concerned with an improvement in apparatus of the type described in United States Letters Patent 2,032,827 issued to me March 3, 1936.

The apparatus described in my prior patent includes an annular pulverizing chamber, jet means to supply a gas under superatmospheric pressure into said pulverizing chamber, a centrally disposed outlet from said chamber, and means for introducing material to be ground into said chamber. The gas is introduced under pressure into said chamber in such manner as to create a re-entrant circulatory path for solid particles larger than predetermined sized ranges. As hereinafter used, the term "re-entrant circulatory path" is employed to describe the flow of solid particles travelling in an inclosed zone or chamber in which solid particles above predetermined size ranges are retained in said zone by centrifugal force and are subjected to the action of high velocity jets of gas and in which the solid particles below predetermined size ranges may be continuously exhausted from the zone by entrainment in gas leaving the same. Reference is made to the apparatus and method described in the above-identified patent, and more particularly to the Figures 1 and 2 thereof for further understanding of the type of apparatus on which the present invention is an improvement.

The present invention is concerned with apparatus for pulverizing solid materials by centrifugal fluid jet action, and more particularly to pulverizing apparatus wherein jets of gaseous fluid are introduced at high velocity into a more-or-less annular grinding zone in an outer portion of a treatment chamber, preferably of circular cross-section, said grinding zone containing material to be pulverized in the form of discrete small pieces. The high velocity fluid jets, or at least most of them, are introduced in directions inclined forwardly in the direction of rotation along said grinding zone so as to maintain the fluid in rapid circulation in the direction of such forward inclinations, either clockwise or counter-clockwise. The grinding zone is confined by peripheral portions of the chamber walls enclosing said zone and at both axial ends, in order to concentrate the discrete solid particles of material in the vicinity of the high velocity fluid jets, as such discrete particles of materials are centrifugated by the rapid fluid circulation in the grinding chamber, so as to promote effective grinding.

The gaseous grinding fluid is continually withdrawn inwardly from the grinding zone and discharged from the treatment chamber, preferably through a centrally disposed fluid outlet. The high velocity fluid jets effect a reduction of particle size of the material under treatment by impact and attrition of particles against one another and against the chamber walls, while at the same time causing the charge of material to circulate rapidly within the grinding zone in the direction of the circulating fluid. Due to the centrifugal effects resulting from the rapid circulation of the charge within the chamber, the larger particles are caused to concentrate in the grinding zone where they come repeatedly under the influence of the introduced high velocity jets and are thus repeatedly subjected to the size reducing action produced thereby, while material which is sufficiently reduced in size is entrained by the gaseous fluid as it spirals inwardly toward the inwardly disposed fluid outlet.

It is a particular object of the present invention to increase the efficiency of centrifugal fluid jet pulverizing apparatus of the type hereinbefore described, thereby to increase its capacity. Another object of the invention is to provide apparatus capable of yielding a product of more uniform degree of fineness or narrower particle size range.

Still another object of the invention is to provide an improvement in apparatus of the type hereinbefore mentioned whereby the effective loading of the fluid jets therein is increased while decreasing the total quantity of discrete solid particles in the apparatus as a circulating load.

It is also an object of the present invention to permit increased loading of jets while supplying a given amount of energy in the grinding fluid, in comparison with prior centrifugal fluid jet pulverizing means.

A particular object of the invention is to provide an improvement in centrifugal fluid jet pulverizers of the type hereinbefore mentioned whereby relatively "wet" materials can be fed to the apparatus and concurrently pulverized and dried.

A principal object of the invention is to provide means for utilizing the energy of high velocity fluid jets in a very effective manner in accomplishing size reduction of pulverulent materials by particle impact and attrition; to provide improved means for subjecting the material to be reduced to the influence of high velocity jets of gaseous fluid; and, to provide means for classifying and controlling the particle size of the fin-

ished product within narrower limits in centrifugal fluid jet pulverizers.

In fluid jet pulverizers, the grinding energy utilized for reduction is usually supplied to the pulverizer by expansion of a gaseous fluid under pressure through nozzles or orifices of restricted cross-section. When air is utilized as the grinding fluid, a fluid pressure of the order of 100 pounds per square inch is commercially readily obtainable; while for installations utilizing steam as the fluid grinding medium, convenient pressures may range from 100 to 500 pounds per square inch with varying degrees of superheat. Of course, particular grinding problems may utilize operating conditions outside the range just specified, but a large proportion of commercial installations are included within the range of conditions outlined.

While the exact mechanism through which energy is transferred from the fluid medium supplying the grinding energy to the material to be reduced is not known, and may be exceedingly complex, this transfer probably takes place chiefly by impact between high velocity fluid jets issuing from the nozzles and particles of material moving at relatively low velocity within the grinding chamber. During such impact momentum is conserved, while some of the available kinetic energy is dissipated in friction and eddies and may account for some of the size reduction obtained. The momentum imparted to the larger particles in various directions will result in shattering impacts between larger particles, between large particles and the walls of the grinding chamber and will result in attrition between the particles of material circulating in the grinding chamber.

In a gaseous fluid pulverizer, it is usually highly desirable to control the maximum particle size in the finished product. This can conveniently be accomplished by providing a classification zone radially inwardly of the grinding zone and by withdrawing the fluid at an inward point of the classification zone. In this manner the gaseous fluid circulating within the mill is caused to spiral inwardly and to exert a frictional drag upon particles suspended in the fluid in a radially inward direction opposed to the centrifugal force acting on the particles resulting from the radial acceleration of their paths of travel, the centrifugal action tending to return the particles outwardly to the grinding zone. By controlling the rate of whirling of the gaseous fluid within the classifying zone with respect to the component of inward flow towards the centrally disposed gaseous outlet, it is possible to control the maximum particle size in the product for which the viscous drag of the fluid is just sufficient to overcome radial acceleration.

In commercial centrifugal fluid-jet pulverizers, it must be realized that the volumetric extent of the grinding chamber is quite small with relation to the rate at which fluid energy is being dissipated, chiefly for grinding purposes. Furthermore, the density of most solid materials subjected to reduction within the grinding chamber is of the order of one thousand times the density of the gaseous fluid supplying the grinding energy. Hence, even though only a small portion of the volumetric contents of the mill may be occupied by the circulating load of discrete solid particles being reduced, such particles constitute a considerable load upon the whirling gaseous fluid, subtracting momentum from the whirling fluid, and dissipating the withdrawn energy in frictional contact with the stationary confining

walls of the grinding chamber and in impacts between particles.

Ordinarily, the gaseous fluid content of the classification zone will be less than one-tenth of a pound, and for accurate control of classification, the momentum of the gaseous fluid present in the classification zone should remain substantially constant. As oversize material reaches the classification zone and is slowed down due to friction, impact or otherwise, such material must be accelerated by the whirling fluid, and hence will reduce the momentum of the fluid. As the oversize material will not reach the classification zone uniformly distributed in time, the momentum of the whirling gas will also vary in time. In order to control classification, it has heretofore been necessary to decrease the circulating load in the grinding chamber by decreasing the rate of feed with respect to the fluid energy input, to such an extent that the minimum rate of whirling still corresponds to the desired classification. Under these conditions, it is found that the available fluid energy is not efficiently utilized in transferring momentum to particles of material in the circulating load for purposes of size reduction by impact and attrition, as sufficient material is not supplied to the high velocity fluid jets, so that a portion of the available energy is lost in transferring momentum to the fluid circulating in the grinding chamber with consequent degrading of the available kinetic energy into heat energy.

Figure 1 is a plan view of apparatus wherein the invention may be practiced.

Figure 2 is a side elevation, partly in section, of the apparatus shown in Figure 1.

Figure 3 is a part plan section taken on line III-III of Figure 2.

Referring to Figures 1 and 2, a circular planar grinding zone 10 is defined by an upper plate 11, a peripheral wall 12, and a rotatable bottom plate 13. It is generally desirable to provide a liner 14 on the inner periphery of the mill and an annular floor ring 15 is provided to seat the rotatable bottom plate 13. The annular floor ring 15 rests upon an annular support 16 which is in turn carried by a vertical cylindrical shell 17. A plurality of clamping members 18, integrally joined to the annular support 16 and shell 17 serve to hold the grinding zone elements together. Thus, by adjusting the position of a cap screw 19, bearing on an annular ring 20 at the outer edge of the top plate 11, and stud bolt 21, which also bears on the annular top plate 11, the pressure tending to hold together the top plate 11 and other members defining zone 10, may be varied.

The top plate may have a facing liner 22, and the circular plate 11 and liner 22 are provided with a centrally disposed outlet pipe 23. The pipe 23 is shown carrying a flange 24 for connecting the mill assembly to a suitable product collection system (not shown). The off take pipe 23 carries a sealing ring 25, seating on the top plate 11 of the grinding zone 10 and an annular ring 26 which may be drawn tightly against the member 27 of the clamping mechanism 18 by means of a stud bolt 28 anchored in the top plate 11.

The peripheral wall 12 and its liner 14 are pierced at a plurality of points around the circumference of the grinding zone 10 to admit nozzles 29 from a circular header 30. Figure 3 shows in particular the arrangement of the nozzles 29 of the peripheral wall 12 of the grinding zone, tangent to a theoretical circle 45 within the zone. The header is supplied with a gas under pressure through an inlet pipe 31.

The rotatable bottom plate is carried at its center on a vertical shaft 32. The upper end of the shaft 32 projects through a centrally disposed opening in the rotating bottom plate 13 and carries a flange 33 integrally joined to the shaft 32. The threaded upper end of the shaft 32 projects above said flange 33 and carries a lock washer 34 and a retaining nut 35. The annular ring 33 is fixed to the bottom plate 13 by a plurality of circumferentially disposed shear pins 36 which will cause the plate 13 to rotate with the turning of the shaft 32. The upper end of shaft 32 is tapered below the bottom plate 13 and a supporting hub 37 rests on the taper. The shear pins 36 extend through the bottom plate 13 into the hub 37.

The lower end of the shaft 32 carries a pulley 38 which may be driven from any suitable power source (not shown). The shaft 32 is journaled in roller bearings 39 and 39' just above the pulley 38.

Inasmuch as the pressure in the grinding zone 10 may be comparatively high at its periphery, it is desirable to maintain gas pressure on the under side of the bottom plate 13, in the space between said plate 13 and the annular supporting member 16. This is accomplished by supplying a gas under pressure through an inlet tube 40, around the shaft 32, providing a passageway 41 upwardly along the shaft and sealing off the shaft 32 from downward flow of gas by a split gland 42 sealed with a suitable high temperature packing 43. The cylindrical shell or casing 17 may be in sections, as shown, and serves as a supporting frame for carrying the working parts of the apparatus. A tube 44 is provided through which material may be fed into the grinding zone 10.

The operation of the apparatus may be described as follows: A gas under pressure is introduced into a header, causing high velocity fluid jets to issue from the peripheral openings in the circular wall of the grinding chamber. The fluid jets are directed forwardly in one direction of rotation and also have an inward component. Material to be reduced is fed into the grinding chamber and, due to the action of the jets, is entrained in the rotating fluid. The larger particles of the material are concentrated by centrifugal action in the radially outward grinding chamber. There such material is picked up by the jets and projected inwardly along their respective axes. The material is then reduced in size by impact. When the material is sufficiently reduced the fluid drag resulting from the radially inwardly component of the fluid flow as the fluid spirals inwardly will overcome the centrifugal force acting on the particles and fine particles of the material will vent from the grinding zone in the exit gas stream.

The bottom plate is rotated in the same direction as the direction of rotation of the fluid within the grinding chamber as indicated by the arrow in Figure 3. Some of the benefits of the invention may be still secured if the bottom plate is rotated in a direction opposite to the direction of rotation of the fluid in the grinding chamber, but the frictional drag on the fluid is increased.

With extremely heavy feed rates, oversize material may reach the classification zone and be slowed down by friction or impact. It then has a tendency to separate out of the fluid due to the effect of gravity. As it comes into contact with the rotating plate, due to friction between the material and the rotating plate, the material is caused to move outwardly into the grinding

zone before it can accumulate in the classification zone in sufficient quantity to cause fluctuations in the rate of whirling in the classification zone. Due to the action of rotating bottom plate in returning oversize material to the grinding zone, sufficient material to efficiently load the high velocity jets introduced into the grinding chamber is obtained with a decreased amount of circulating load in the treatment chamber, as the circulating load is kept concentrated along the peripheral wall where it can be acted upon by the introduced high velocity jets. At the same time the classification zone is kept free from possible accumulations of oversize material which would be likely to withdraw momentum from the fluid in the classification zone at a widely varying rate, with a resulting variation in the classifying action.

The following example illustrates the practice of my invention but is not to be construed as limiting the same: A North Carolina clay, in approximately 8 mesh particle size, was introduced into an apparatus constructed substantially as shown in the drawings. The diameter of the grinding chamber was 20 inches, the distance between the top and bottom plates was 1 1/4 inches, and the spacing between the rotating bottom plate and the annular floor ring was 0.015 inch. The bottom plate was rotated at 1150 revolutions per minute. Air was supplied to the underside of the rotating bottom plate at a pressure of 100 pounds per square inch to seal the plate. Eight number two drill jets were employed on the periphery of the mill set tangential to a theoretical 9 inch diameter circle within the mill. The feed was injected with steam supplied at a pressure of 120 pounds per square inch and was fed into the grinding chamber at a substantially uniform rate at 360 pounds per hour. Steam at a temperature of approximately 660° F. was supplied to the jets under a pressure of 120 pounds per square inch, at a rate of approximately 1800 pounds per hour. The product obtained gave a particle size analysis of less than 0.35% on a 325 mesh screen and was predominantly below 15 microns in size.

By way of illustrating the increase in output obtained according to the present invention the following illustration is given: In a mill constructed substantially as described in the preceding example it was determined that 325 pounds per hour of ball clay used in the porcelain enamel industry could be processed with 340 cubic feet per minute of free air supplied at a pressure of 100 pounds per square inch. The products had a particle size analysis of less than 0.3 percent on a 325 mesh screen and was 10-15 micron average size. In a mill similar in all other respects save the use of a rotatable bottom plate, it was found that the maximum feed rate which could be maintained with the same quantity of air at the same pressure was only 250 pounds per hour and the product showed 2.1 percent on a 325 mesh screen with a 15-18 micron average particle size.

In some instances a portion of the circulating load in the grinding chamber will be composed of fairly large particles, for instance, from 10 to 15 mesh material. With some materials, such particles may circulate for a time without being actively engaged by the high velocity fluid jets. Such particles circulate by bouncing along the outer peripheral wall, withdrawing energy from the grinding fluid and dissipating the energy with the stationary walls of the grinding chamber. Under such circumstances, it is of advantage to attach projections, such as rods, plates and other

protuberances, to the rotating bottom plate. Thus, the rotation of the plate causes the projection to engage or impact particles bouncing along the peripheral wall into the grinding chamber and return the particles outwardly more rapidly. In this manner the circulating load is further concentrated along the peripheral wall where it can be acted upon by the high velocity jets. Thereby the jets can be efficiently loaded with a further reduction of circulating load in the treatment chamber.

While the rotation of the floor or bottom plate of the grinding zone yields the greater advantage, it is of benefit, when certain materials are to be pulverized, to rotate the top confining member of the pulverizing chamber casing. In some instances, it is unnecessary that the rotatable member forming a portion of the casing for confining the flowing gas stream be driven. The said member may be free to rotate, thus taking less energy from the grinding fluid merely to keep the rotatable member spinning than is taken from the gas by a stationary casing member.

An advantage of the apparatus herein described arises out of the fact that a feed containing a higher percentage of moisture can satisfactorily be ground. It must be recognized that the increased capacity obtainable with the apparatus of the present invention will vary with the material being treated. With certain materials only a relatively small increase in throughput of solid per unit of energy introduced in the gas is obtained, although a more uniform product, as to particle size, invariably results. With other materials, increased capacities up to as much as thirty percent or more can be obtained. The general shape of the pulverizing chamber need not neces-

sarily be planar, but the top and bottom portions may be somewhat convex or slightly concave.

I claim:

- 5 1. In a centrifugal fluid jet pulverizer, the combination of: a generally circular planar pulverizing chamber for confining a flowing gas stream; means to introduce a gas under superatmospheric pressure into said casing at a plurality of points from the periphery thereof tangential to a theoretical circle within the casing to create a gaseous jet pulverizing zone in the form of a re-entrant circulatory path for solid particles larger than predetermined size ranges; a rotatable member forming at least a part of the bottom of said pulverizing zone; a centrally disposed outlet from the top of said chamber; means to introduce solid particles to be reduced in size into said chamber near the periphery thereof; and, means to rotate said rotatable member in the direction of flow of said gas stream.
- 10 2. In a centrifugal jet pulverizer, the combination of: a casing for confining a flowing gas stream; means to introduce a gas under superatmospheric pressure into said casing to create a gaseous jet pulverizing zone in the form of a re-entrant circulatory path for solid particles larger than predetermined size ranges; means to introduce solid particles to be reduced in size into said gas stream; a rotatable member forming at least a portion of the confining wall of the pulverizing zone and rotating in the direction of flow of said gas stream to assist in returning solid particles larger than predetermined size ranges to the action of the gaseous jets; and, an offtake from said pulverizing zone inwardly disposed with respect to said re-entrant circulatory path of solid particles.

NORWOOD H. ANDREWS.
